UNITED STATES PATENT OFFICE.

JOHN C. BACKERT, OF BROOKLYN, NEW YORK.

CUTTING-MACHINE FOR RULES AND SLUGS.

1,114,329.

Specification of Letters Patent.

Patented Oct. 20, 1914.

Application filed October 15, 1913. Serial No. 795,209.

To all whom it may concern:

Be it known that I, JOHN C. BACKERT, a citizen of the United States, residing at Brooklyn, county of Kings, State of New York, have invented certain new and useful Improvements in Cutting-Machines for Rules and Slugs, of which the following is a full, clear, and exact description.

My invention relates to an improved apparatus for cutting rules, slugs and the like, such as used by printers, the object being to provide a simple and effective means for accomplishing this purpose, which means may be readily manipulated and the slugs and rules may be cut off square or beveled and may likewise be milled or smoothed up at the ends.

In the drawings Figure 1 is a plan view of the complete machine on a reduced scale. Fig. 2 is a front elevation thereof. Fig. 3 is a relatively enlarged detail plan view of a part of a mechanism as it would appear in operation. Figs. 4, 5 and 6 are views of details.

1 is a supporting frame. 2 is a table carried thereby, upon which the work is placed. 3 is a back pivoted at 4 at one side of the table.

5 is a latch by which the back 3 may be held in different positions, that is to say, the position shown in Fig. 1, wherein the rules or slugs are to be cut off square, or the dotted position indicated in Fig. 3, where the rules or slugs are to be beveled, this latch 35 being of the plunger type and coöperating with sockets, as 2^a, in the table 2.

6 represents a bunch of slugs in place on the table 2 and held against the back 3 ready to be cut and trimmed at the ends. The

40 holding means comprises a ratchet slide 7 provided with a pad-like handle 8 at the front end, which permits the slide 7 to be pushed ahead. In the front end of the slide 7 is a spring-pressed plunger 9, which engages directly with the slug or bunch of slugs 6. The ratchet is best seen in Fig. 4, wherein the ratchet teeth 10—10 are shown on the lower side of the plunger 7, with an appropriate pawl 11 arranged adjacent 50 thereto.

12 is a guide for the slide 7, said guide being provided with a spring-pressed stud 13 designed to yieldingly hold the rod 7 down against the ratchet 11. As the rod 7 55 is pushed ahead, the teeth slip over the

pawl 11 until the plunger 9 engages the slug, or bunch of slugs, and puts the spring 9^a under compression. The slide 7 is retained in this position by the pawl 11. When the slug or slugs are held in place by the plunger 9 under the action of spring 9^a, the ends of the slug or slugs project beyond the edge of the table to the desired degree to be cut off and trimmed by a cutter 14. The table 2 is mounted on a suitable guide 65 means such as the rods 15—15, so that said table may slide to and fro.

The tool 14 is driven by a suitable shaft 16, whereby it may be driven from any suitable source of power. It may have a fly-wheel 17 with a crank handle 18, so that the fly-wheel may be turned by hand. The table 2, when the cutter is rotating, may be drawn in a direction to bring the slugs into engagement with the cutter, which attacks and cuts 71 off the same, the face of the cutting tool 14 being appropriately designed to trim and smooth the adjacent end of the slugs.

By preference I provide mechanical means for moving the table, although this is not essential in all cases. One simple form of mechanical means for moving the table in a direction to cut the slugs is illustrated in the drawings, said means comprising a spur gear 19 on the shaft 16 meshing with the 80 spur gear 20 on a countershaft 21, which latter carries a pinion 22 meshing with a rack 23 on the underside of the table 2. Obviously, as the fly-wheel rotates in the direction of the arrow (Fig. 1) the table will 85 be moved in a direction to cause the slugs to move toward the cutter, the speed being determined by the ratio of the gearing, which may be modified at will.

Means is preferably provided to shift the 95 gearing into and out of effective engagement. This means may comprise a yoke 24 embracing a grooved collar on the gear 20, which latter may be fixed to the shaft 21, so that by shifting the yoke 24 to the right the gear 20 may be disengaged from the gear 19 and the pinion 22 disengaged from the rack 23, leaving the table free to be moved 100 by hand.

26 is a gage which may be effectively employed for assisting the user in properly placing the slug or rule in place on the table against the back 3, and to determine the length of said slug when finished. This gage 26 is slidably mounted upon the hinged 105 110

back 3 and is provided by preference with an adjusting screw 27 which may have a handle 28 to secure delicate adjustment. For a quick adjustment, means is provided to release the gage from the adjusting screw 27, said means comprising a spring-pressed pivoted sector 29 with a threaded face arranged to engage the screw 27. This sector is provided with a finger-piece 30, by which it 10 may be tilted to be disengaged from the screw, whereupon the gage 26 may be shifted quickly to approximately the final position, the said final position being accurately determined by turning the handle 28 and the 15 adjusting screw 27.

In Fig. 1, I have shown the back in position to cut off the rules or slugs at right angles, whereas in Fig. 3 I have shown in dotted lines the position of the back when 20 adjusted so as to cut off a rule or slug at a bevel.

31 is an adjustable stop-screw which is carried, by the table 2 or an offset part thereof, as indicated at 32, said screw being 25 arranged to engage a fixed abutment 33 on the frame 1 when the table is fed forward, the purpose of the adjustable stop being to limit the forward movement of the table so as to check its advance after the back 3 has 30 passed the cutting tool. As soon as a slug or rule has been cut off and the work completed, the said slug or rule may be quickly removed by simply lifting the outer end of the rod 7, disengaging the same from the 35 pawl 11, whereupon it may be quickly and easily drawn back, freeing the spring-pressed plunger 9 from the finished slug, which may then be withdrawn.

In the preferable construction, the guide 40 12 is adjusted laterally of the table 2, it having a suitable base 12^a guided in the transverse undercut groove 2^a in the table 2. As rules or slugs of different lengths 45 are employed, it is desirable to engage the said rules or slugs at different distances from the cutter, which may be easily determined and varied by simply shifting the guide 12 laterally in the groove 2^a so as to bring the plunger 9 into engagement with 50 the rules or slugs at the most effective position.

As shown in Figs. 5 and 6, the face of the tool 14 is provided with radial cutters which operate as milling faces so designed 55 as to effect fine or delicate work. When the cutter is rotated for milling purposes, the gears for feeding the table 2 may be disengaged by shifting the yoke 24 to the right (Fig. 2).

60 The table in its preferable construction is mounted upon two parallel transverse guides such as indicated at 34 (Fig. 2), by which the edge of the table adjacent the

cutter may be moved toward and from the cutter to get the proper adjustment.

65

What I claim is:

1. In a device of the character described, a movable table, a cutter supported independently of said table and positioned adjacent the edge thereof, a back on said table 70 having a fixed pivot and adjustable thereabout, a gage cooperating with said back, means on said table for engaging and holding a rule or slug against said back with an end projecting therefrom in the direction 75 of said cutter, said holding means being adjustable relatively to the table and to the back.

2. In a device of the character described, a movable table, a cutter supported independently of said table and positioned adjacent the edge thereof, a back on said table 80 having a fixed pivot and adjustable thereabout, transversely of the said table edge, a gage cooperating with said back and adjustable longitudinally thereof, means on 85 said table for engaging and holding a rule or slug against said back with an end projecting therefrom in the direction of said cutter, said holding means being adjustable 90 relative to said back and table.

3. In a device of the character described, a table, a cutter supported independently of said table and positioned adjacent the edge thereof, a back mounted on said table having a fixed pivot and adjustable thereabout 95 transversely of the table edge, a gage carried by and adjustable longitudinally of said back, means for holding a rule or slug against said back and gage with an end projecting from said back in the direction of 100 said cutter, and means for effecting relative bodily movement between said table and cutter to bring said rule or slug into operative contact with said cutter.

105

4. In a device of the character described, cutting means, a work-supporting table positioned adjacent thereto and provided with a back extending upwardly from the face thereof, and means for holding a rule or 110 slug against said back with an end projecting therefrom in the direction of said cutting means, said holding means comprising a guide member slidably mounted on said table, a hand operated member extending 115 through said guide and slidably toward and from said back, said member having a separate and resilient end portion for engaging said rule or slug, and means for holding said member at various positions in 120 said guide.
